UNITED STATES PATENT OFFICE.

CHARLES E. DERR, OF DETROIT, MICHIGAN, ASSIGNOR TO PACKARD MOTOR CAR COMPANY, OF DETROIT, MICHIGAN, A CORPORATION OF MICHIGAN.

GEAR-CUTTING MACHINE.

1,297,332.

Specification of Letters Patent. Patented Mar. 18, 1919.

Application filed May 27, 1914, Serial No. 841,822. Renewed January 18, 1919. Serial No. 270,946.

To all whom it may concern:

Be it known that I, CHARLES E. DERR, a citizen of the United States, and resident of Detroit, Wayne county, State of Michigan, have invented certain new and useful improvements in Gear-Cutting Machines, of which the following is a specification.

This invention relates to gear cutting machines, and particularly to machines for cutting oblique or skewed teeth in bevel gears.

One of the objects of the present invention is to provide a novel and efficient form of adjustment for the guiding means of the tool carrier and to permit of the adjustment of the tool so that the angle of its cutting face relative to its path of travel may be varied.

Other objects of the invention will appear from the following description taken with the drawings which form a part of this specification and which illustrate one embodiment of the invention.

In the drawings:

Figure 1 is a plan view of a machine embodying the invention;

Fig. 2 is a side elevation of the machine shown in Fig. 1;

Fig. 3 is a side elevation from the other side of the machine;

Fig. 4 is a vertical section approximately on the line 4—4 of Fig. 1;

Fig. 5 is a vertical section approximately on the line 5—5 of Fig. 1;

Fig. 6 is a vertical sectional view through a part of the tool carrier and the tool holder; and

Fig. 7 is a section on the line 7—7 of Fig. 6.

Referring to the drawings, the frame or bed of the machine is indicated at 10, and at one end thereof is a blank supporting mechanism, the spindle 11 of which is shown in Fig. 1 as supporting the blank B. Any suitable means may be employed for producing a relative rolling motion between the blank and the cutter to generate the tooth, such as that illustrated in Patent No. 665,054, in which the blank is rolled on its pitch surface for this purpose.

At the other end of the machine is mounted a ram 12 in a slideway 13, and a fly-wheel 14 reciprocates the ram through a connecting rod 15 eccentrically pivoted to the fly-wheel at 16 and pivoted to the ram at 17.

18 represents the operating head of the ram, upon which is mounted a tool carrier or support 19, having a transverse sliding connection with the operating head as by the dove tail 20 and slideway 21. The tool support comprises a pair of separated uprights 22 between which is pivoted a tool apron 23 having a forwardly extending part 24 in which the tool holder 25 is mounted. A spring 26 secured to the support at one end and to an adjusting bolt 27 on the apron holds the latter yieldingly in normal or cutting position. The apron may be raised from cutting position, as on its return stroke, by a cam mechanism comprising an arm 28, keyed to the pivot 29 of the tool apron 23, a cam 30, shown in dotted lines in Fig. 2, a shaft 31 upon which said cam is mounted and which has a sliding keyed connection 32 with a bevel gear 33 supported in a bracket 34 on the operating head 18 of the ram, a companion gear 35 having a similar sliding keyed connection 36 with a shaft 37, a bevel gear 38 on said latter shaft, and a segment 39 meshing with the gear 38 and mounted on a bell crank 40 operated by a cam 41 formed in the fly-wheel 14 hereinabove referred to. It will be understood that the sliding connection 36 allows for the sliding movement of the ram 12 and the connection 32 for the transverse motion of the tool support 19 relative to the ram.

Means are provided for operating in conjunction with the reciprocating movement of the ram 12, to give to the tool support a movement in a generally oblique path relative to the face of the blank B. In the embodiment of the invention shown this means comprises principally a cam plate 42 having a cam slot 43 therein, and a pin or roller 44 mounted on the tool support 19 and co-operating with said cam slot. For the purpose of supporting the pin 44 adjacent the plate 42 the support 19 is formed with an arm 45 which may be an integral part of the support. The pin 44 is secured therein by a suitable sleeve 46 and nut 47, its lower end and the roller are lubricated by a grease cup 48 feeding lubricant through a central channel in the pin. Thus, as the ram 12 moves forwardly, the latter is at the same time caused to slide laterally conforming to the path of the cam slot 43, and with a cam slot as shown herein, the tool moves in a generally oblique and some-

what curved path cutting a skewed or obliquely curved tooth in the blank.

For the purpose of causing the pin 44 to travel constantly against one wall of the cam slot 43 a spring 49 is provided. This spring is supported on a rod 50 between an upright bracket 51 on the operating head 18 and a similar bracket 52 on the sliding tool support 19. The rod 50 is supported in said brackets being secured to one and arranged to slide in the other. The spring being under compression at all times there is a constant tendency to press the pin 44 against the outside face of the cam slot 43.

15 The cam plate 42 is mounted for adjustment in two distinct respects, that is, about an axis which alters the obliquity of the cam slot, and bodily transversely of the machine. To obtain the first of these adjustments the 20 plate is mounted upon a support or table 53 upon which are a series of studs 54 (three are shown), which project into arc-shaped slots 55 in the plate. These slots are arranged about a common center so that the 25 plate may be turned on a trunnion 55' the axis of which preferably lies somewhere in the cam slot 43 as shown, the pin 44 being positioned at that point in Fig. 1 of the drawings, thus making easier the adjustment 30 of the plate. The movement of the cam plate is obtained through bolts 56 in a flange 57 on the table 53, one bolt being loosened and the other tightened to turn the plate, and a scale 58 is provided to show the 35 degree of angularity of the cam slot. When the plate is properly positioned relative to the table it is secured thereto by tightening the studs 54.

The other adjustment of the cam plate 40 is obtained by moving the table 53. For this purpose the table has a dovetail 59 mounted in a slideway 60 in a suitable part of the frame or bed of the machine, as in the bracket 61, this slideway being arranged 45 transversely of the machine and the table being movable bodily in it. The table is adjusted on the machine by a positioning bolt 62 which may be screwed into the bracket 61 a greater or less distance as desired, the 50 flange 63 on said bolt carrying the table with it through the medium of the piece 64 secured to the outer edge of the table. The lock nuts 65 secure the bolt 62 in adjusted 55 position and carry the table with them in the outward adjustment of the bolt. A scale 66 shows the degree of adjustment of the table relative to the frame of the machine.

It will be observed that, as shown in the drawings, the tool holder 25 extends in a 60 generally oblique direction, being approximately parallel with the general direction of the cam slot 43, so that the face *t* of the tool T, mounted in the tool holder is substantially at a right angle to the general direction of travel of said tool. Since the cam

plate 42 is so mounted that the degree of obliquity of the cam may be changed, it is desirable that the tool be so mounted that it may be readily adapted to the various angles of the cam slot and its face always 70 maintained at the most nearly correct cutting angle. In the present embodiment of the invention the tool holder 25 is so mounted in the support 19 that its forward end may be shifted from one side to the other 75 relative to the forwardly extending part 24 and thus vary the angle of the face *t* of the tool relative to its path of travel. The holder 25 is shown as having a boss 67 forming a pivot for the holder and secured in a 80 socket 68 in the apron 23 by means of a bolt 69. This permits the front end of the holder to swing laterally between ears 70 on the part 24 above referred to. Bolts 27 in said ears position and hold the tool holder, as 85 shown particularly in Fig. 7. A second boss 72, at the front end of the holder extends upwardly through a slot 73 in the part 24, and a nut 74 serves to clamp the tool holder when positioned.

90 It will be seen that the tool T, which is V-shaped in cross section, is arranged in a longitudinal slot 75 in the holder 25 and secured therein by a bolt 76 passing through the boss 72 and accessible at the upper projecting end of the latter. A positioning plate 77 is secured to the front face of the holder 25 over the slot 75 to locate the front face *t* of the tool as shown in the drawings.

95 It will be understood that the invention 100 is not limited to the specific form shown herein, but is capable of modification in various ways without departing from the spirit or scope of the claims.

Having thus described my invention, what 105 I claim and desire to secure by Letters Patent is:—

1. In a gear cutting machine, the combination with blank holding mechanism, of a tool carrier and tool, means for operating 110 the carrier to cause the tool to travel in a generally oblique path across the face of the blank, said means being adjustable to change the degree of obliquity of said path, and means for adjusting the tool to vary 115 the angle of its cutting face relative to its path of travel.

2. In a gear cutting machine, the combination with blank holding mechanism, of a tool carrier and tool, means for operating 120 the carrier to cause the tool to travel in a curved path on an arc of a circle and in a generally oblique direction across the face of the blank, said means being adjustable to change the position of the axis of said arc, 125 and means for adjusting the tool to vary the angle of its cutting face relative to its path of travel.

3. In a gear cutting machine, the combination with the frame, of a tool carrier, means 130

for moving the tool carrier, a cam plate for guiding said carrier in its movement, means for adjusting said cam plate about an axis, and means for adjusting the axis relative to the frame.

5. In a gear cutting machine, the combination with the frame, of a tool carrier, means for moving the tool carrier, a cam plate for guiding said carrier in its movement, means for adjusting said cam plate about an axis, and means for bodily sliding the cam plate horizontally relatively to the frame.

6. In a gear cutting machine, the combination with the frame, of a tool carrier, means for moving the tool carrier, a cam plate for guiding said carrier in its movement, a support on which said cam plate is adjustably mounted, and means for adjusting said support relative to the frame.

20. 6. In a gear cutting machine, the combination with the frame, of a tool carrier, means for moving the tool carrier, a cam plate for

guiding said carrier in its movement, a support for said cam plate, means for adjusting and holding said cam plate on said support, 25 and means for adjusting and holding the support on the frame.

7. In a gear cutting machine, the combination with the frame, of a tool carrier, means for moving the tool carrier, a cam plate for 30 guiding said carrier in its movement, a support for said cam plate, means for adjusting said cam plate about an axis on said support and locking it in adjusted position, and means for adjusting the support with a 35 movement of translation relative to the frame and for locking it in adjusted position.

In testimony whereof I affix my signature in the presence of two witnesses.

CHARLES E. DERR.
